Hazeltine Corporation, Jersey City, N. J., a cor-
poration of Delaware

Original application May 22, 1934, Serial No.
726,931. Divided and this application January
14, 1936, Serial No. 59,021

6 Claims. (Cl. 250—36)

This invention relates to oscillation circuits tunable over a range of frequencies by an adjustable reactance thereof to select a desired frequency of the range, and more particularly to such circuits including provisions for independently adjusting the resonant frequency thereof relative to the selected frequency over a small fraction of the tuning range.

This application is a division of my copending 10 application Serial No. 726,931, filed May 22, 1934.

In an oscillation circuit containing inductance and capacitance, one of which is adjustable for tuning the circuit over a desired range, it is sometimes desired to adjust the resonant frequency 15 thereof, relative to the frequency selected by the tuning reactance, over a small fraction of such tuning range. Such an adjustment may be useful for various purposes as, for example, shifting the frequency of the oscillator of a superheterodyne receiver relative to the signal frequency to adjust the selectivity of the system, to which feature my above-mentioned copending application is directed. Such adjustment of the 20 oscillation frequency may be effected by providing in connection with the circuit adjustable auxiliary impedance means. However, the reactance of the adjustable tuning element of the circuit varies within wide limits as the element is adjusted to tune the circuit over its range. The 25 effectiveness of the auxiliary impedance means in adjusting the resonant frequency of circuit is ordinarily dependent on the relative magnitude of its impedance and those of the main reactance elements of the circuit. Therefore, the effectiveness of the auxiliary impedance means tends 30 to vary in accordance with the frequency to which the circuit is tuned and, in order to obtain equal 35 adjustments of the resonant frequency of circuit relative to different selected frequencies, different 40 degrees of adjustment of the auxiliary means would ordinarily be required. It is highly desirable, however, that equal adjustments of said auxiliary impedance means will effect equal 45 adjustments of the resonant frequency of the circuit for all frequencies of the range through which the circuit may be tuned.

It is the primary object, therefore, of the present invention to provide a circuit arrangement whereby the resonant frequency of an oscillation circuit, tunable to any selected frequency within a predetermined range of frequencies may be adjusted relative to the selected frequency, and independently of the tuning means over a small fraction of the range, equal adjustments 55 of the adjusting means effecting equal changes

of the resonant frequency of the circuit relative to the selected frequency for all frequencies of the range. For a better understanding of my invention, together with other and further objects thereof, reference is had to the following description taken in connection with the accompanying drawing, and its scope will be pointed out in the appended claims.

In accordance with the present invention, an oscillation circuit is provided with auxiliary adjustable impedance means, independent of the tuning element of the circuit, and coupled to the circuit to adjust the resonant frequency thereof. The auxiliary means and its coupling to the circuit are so proportioned and arranged that the effectiveness thereof is substantially constant and independent of the frequency to which the circuit is tuned by its tuning element.

In a preferred embodiment of the invention, the oscillation circuit is comprised in an oscillation system, the auxiliary adjustable impedance means comprises a variable condenser connected across a portion of the capacitance of the circuit through at least a portion of the inductance of the system, and the auxiliary condenser and its connections are so proportioned and arranged as to provide the desired constancy in effectiveness of the auxiliary variable condenser for any selected frequency within the operating range of the system.

In the accompanying drawing Fig. 1 is a circuit diagram of a complete superheterodyne receiver, partly schematic, illustrating the present invention applied to the local oscillator to adjust the selectivity of the receiver, as disclosed in my aforesaid copending application, while Fig. 2 shows graphically the relation between the several frequencies of the system.

Referring now to Fig. 1, there is illustrated a superheterodyne receiver comprising, in cascade, an antenna and ground system 10—11; a radio-frequency amplifier 12, an oscillator-modulator tube 13; an intermediate-frequency amplifier 14; and a detector, audio-frequency amplifier and loud-speaker 15. The devices 12, 14 and 15 are indicated only schematically, since they constitute no part of this invention and may be of any conventional design.

The oscillator-modulator tube 13 is of the hexode type and may take the form disclosed in Patent No. 2,015,327 issued to Harold A. Wheeler on September 24, 1935. The tube contains a signal input grid 16 coupled to the radio-frequency amplifier 12 through a radio-frequency transformer 17, the secondary coil of which is tunable 55

to signal channels of the broadcast range by a variable condenser 18.

There is associated with tube 13 an oscillation system 19, embodying the present invention, which includes a coil 20 connected from an inner screen 21 to an inner grid 22 through a condenser 23. A condenser 24 is connected between ground and an intermediate point 25 of the coil. A source of positive operating voltage, designated 10 +B, is connected through a resistor 26 to the point 25 for supplying a proper direct voltage to the screen 21. A variable condenser 27 is connected between ground and the upper end of coil 28. The condensers 24 and 27 and the portion 15 of coil 20 above point 25 constitute a resonant circuit which determines the frequency of the oscillation system, this frequency being variable by means of condenser 27. The oscillator-modulator circuit just described is similar to those 20 which are more fully described in United States Letters Patent No. 1,958,027, granted May 8, 1934, upon the application of Harold A. Wheeler.

In accordance with the present invention, there is connected a relatively small variable condenser 28 between ground and a second intermediate point 29 of coil 20 which is outside the resonant frequency-determining circuit. By reason of its connection to ground, condenser 28 is connected across condenser 24 and a portion 30 of coil 20 which is outside the resonant circuit. The function and operation of condenser 28 will be more fully explained subsequently.

Modulation occurs between the received signal frequency impressed on grid 16 and the local oscillator frequency in a manner which is fully described in the above-mentioned Patent No. 1,958,027. The products of modulation at the circuit of anode 30 include the intermediate-frequency band which is the difference between the local oscillator frequency and the frequencies of the received signal channel. For the purpose of maintaining a constant frequency difference and therefore a constant intermediate carrier frequency, the variable condensers 18 and 27 are 45 ganged together for simultaneous operation by means of a unicontrol device indicated generally by U.

A coupling system 31 connected between the anode 30 of tube 13 and the input of the intermediate-frequency amplifier 14 is tuned to pass a fixed intermediate-frequency band.

The frequency band selected and passed by the tuned coupling system 31 is shown graphically in Fig. 2. In this figure, the intermediate carrier 55 frequency is represented by the vertical line A which is taken as 175 kilocycles in this case. The coupling system is adjusted to select and pass an intermediate-frequency channel band 8 kilocycles wide, from 171 to 179 kilocycles, these two 60 edges of the selected band being indicated by the broken lines B and C, respectively.

The function of the condenser 28 associated with the oscillator circuit is to shift the oscillator frequency in either direction by any desired 65 amount up to the width of a side band, without altering the radio-frequency channel selected. Since the side-band width for the case under consideration is 4 kilocycles, this should be the limit of frequency shift due to condenser 28. It will 70 be noted that this range of adjustment is a very small fraction of the tuning range of the system, which is usually of the order of 1000 kilocycles to cover the general broadcast band. If the oscillator frequency is higher than the received signal 75 frequency, as is usually the case, any decrease in

the oscillator frequency without an attendant change in the selected radio frequency, will shift the intermediate carrier frequency downward by a like amount, and vice versa. In the example under consideration, therefore, the oscillator frequency will be considered to be 175 kilocycles higher than the selected signal frequency, when condenser 28 is in its neutral or normal position. The dotted line D in Fig. 2 shows the location of the intermediate carrier frequency when the oscillator frequency is shifted downward by 3 kilocycles from normal. It is contemplated that the intermediate frequency represented by line D may be shifted at will to any position between the limits of lines B and C.

Since the position of the intermediate-frequency band selected by the coupling system 31 and the intermediate-frequency amplifier 14 remains fixed, such a shift of the derived intermediate carrier frequency has the effect of cutting off the outer frequencies of one side band and of adding on to the outer frequencies of the other side band by a like amount. For the amount of shift illustrated in Fig. 2, there remains in the lower side band only the frequencies between 171 and 172 kilocycles, corresponding to audio frequencies from 0 to 1000 cycles. The lower intermediate-frequency side-band frequencies corresponding to audio frequencies of 1 to 4 kilocycles have not been selected. The upper intermediate-frequency side band, however, is now 7, instead of 4, kilocycles wide; for it now extends from 172 to 179 kilocycles. Hence, instead of transmitting only frequencies corresponding to 0 to 4 kilocycles of audio frequency, the selecting system now transmits frequencies corresponding to 0 to 7 kilocycles of audio frequency.

In the manner just described, the audio-frequency fidelity is improved without increasing the transmitted band width; although it should be noted that at the same time frequencies corresponding to low audio frequencies (0 to 1000 in this case) are transmitted with better efficiency than the frequencies corresponding to higher audio frequencies. The reason for this is that frequencies corresponding to low audio frequencies are transmitted by both side bands. This inequality of transmission can be compensated to a considerable extent by a properly designed equalizing network in the audio-frequency amplifier.

It is noted that the arrangement of condenser 28 is particularly advantageous. By reason of its connection across at least some of the capacitance of the frequency-determining circuit and across inductance which is outside the frequency-determining circuit, equal adjustments or variations of the capacitance of condenser 28 produce equal frequency shifts or adjustments at all frequencies of the tuning range. Such would not be the case if condenser 28 were connected across inductance alone or capacitance alone.

As is well understood, the condenser 24 has a maximum effect in the circuit with maximum adjustment when the condenser 27 is adjusted to its maximum value to provide a minimum reactance for tuning the circuit to a lower frequency of the range, and has a minimum effect when the condenser 27 is adjusted to its minimum value to provide a maximum reactance for tuning to higher frequencies of range. If, therefore, the condenser 28 were connected only across the condenser 24 so that its effect would vary with frequency in the same manner as the condenser 24,

similar adjustments of this condenser would consequently effect different degrees of changes in the resonant frequency of the circuit at different frequencies of its tuning range. By arranging the circuit in accordance with the present invention, however, with the condenser 28 and the lower part of the inductance 20 in series, connected across the condenser 24, the reactance of this portion of the inductance 20 varying with frequencies in an opposite sense to that of the condenser 28, the resultant capacitive reactance of the auxiliary frequency adjusting circuit in parallel with the condenser 24 is modified so that equal adjustments of condenser 28 effect equal changes in the resonant frequency of the circuit at all frequencies of its tuning range.

Since the intermediate carrier frequency may be shifted in either direction, the direction chosen for the shift will ordinarily be opposite that in which an interfering signal may happen to be present. Such a shift will tune out such an interfering signal at the same time that the fidelity is being improved.

While I have described what I at present consider the preferred embodiment of my invention, it will be obvious to those skilled in the art that various changes and modifications may be made therein without departing from my invention, and I, therefore, aim in the appended claims to cover all such changes and modifications as fall within the true spirit and scope of my invention.

What is claimed is:

1. An oscillation circuit tunable over a range of frequencies and including an adjustable reactance element for tuning said circuit to a selected frequency of said range, and means adjustable independently of said tuning element for adjusting the resonant frequency of said circuit relative to said selected frequency over a small fraction of said range, comprising auxiliary adjustable impedance means coupled to said circuit, the impedance of said auxiliary impedance means being so related to its coupling to said circuit that equal adjustments thereof effect substantially equal adjustments of the resonant frequency of said circuit for all frequencies of said range.

2. An oscillation circuit tunable over a range of frequencies and including an adjustable reactance element for tuning said circuit to a selected frequency of said range, and means adjustable independently of said tuning element for adjusting the resonant frequency of said circuit relative to said selected frequency over a small fraction of said range comprising variable capacitance means coupled to said circuit, the reactance of said variable capacitance means being so related to its coupling to said circuit that equal adjustments thereof effect substantially equal adjustments of the resonant frequency of said circuit for all frequencies of said range.

3. An oscillation circuit tunable over a range of frequencies and including adjustable reactance means for tuning said circuit to a selected frequency of said range, and auxiliary impedance means adjustable independently of said tuning element for adjusting the resonant frequency of said circuit relative to said selected frequency, said auxiliary means including serially connected reactance means of opposite types, at least a part

of said auxiliary impedance means being adjustable and said means being connected in parallel with at least a part of the reactance of said circuit and the reactance of said auxiliary means being so related to that of said part of said circuit with which it is connected in parallel that equal adjustments of said adjustable part of said auxiliary impedance means effects substantially equal adjustments of the resonant frequency of said circuit for all frequencies of said range.

4. An oscillation circuit tunable over a range of frequencies and including inductance means and a variable condenser effectively connected across at least a portion of said inductance means for tuning said circuit to a selected frequency of said range, and means adjustable independently of said variable condenser for adjusting the resonant frequency of said circuit relative to said selected frequency over a small fraction of said range, comprising an auxiliary adjustable condenser connected in parallel with at least a portion of said circuit including at least a portion of the capacitance of said circuit and at least a portion of said inductance, the reactance of said auxiliary condenser being so related to that of the portion of said circuit with which it is connected in parallel that equal adjustments of said auxiliary condenser effect substantially equal adjustments of the resonant frequency of said circuit for all frequencies of said range.

5. An oscillation system comprising a vacuum tube and an oscillation circuit, tunable over a range of frequencies, associated with said tube and including an adjustable reactance element for tuning said circuit to a selected frequency of said range, and means adjustable independently of said tuning element for adjusting the resonant frequency of said circuit relative to said selected frequency over a small fraction of said range, comprising auxiliary adjustable impedance means coupled to said circuit, the impedance of said auxiliary impedance means being so related to its coupling to said circuit that equal adjustments thereof effect substantially equal adjustments of the frequency generated by said system for all frequencies of said range.

6. An oscillation circuit tunable over a range of frequencies and including inductance means and variable capacitance means effectively connected across two points of said inductance for tuning said circuit to a selected frequency of said range, said capacitance means having an intermediate connection point, and means adjustable independently of said variable capacitance means for adjusting the resonant frequency of said circuit relative to said selected frequency over a small fraction of said range, comprising an auxiliary variable condenser connected between a third point of said inductance and said intermediate point of said capacitance means, the reactance of said auxiliary condenser being so related to that of the portion of said circuit across which it is connected that equal adjustments of said auxiliary condenser effect substantially equal adjustments of the resonant frequency of said circuit for all frequencies of said range.

JOHN KELLY JOHNSON.
